UNITED STATES PATENT OFFICE.

DANIEL BRIGGLE, OF BLOOMDALE, OHIO.

LOADING DEVICE.

Application filed August 14, 1925. Serial No. 50,289.

This invention has reference to a loading device and more particularly a loading device of the portable type especially designed for loading manure, dirt or the like.

5 An important object of the invention is to provide means whereby the scoop or prongs forming a part of the device, will be automatically dumped at a point adjacent to the lower end of the endless conveyor.

10 A further object of the invention is to provide a novel form of scoop whereby the scoop will be held against dumping until the scoop has reached its proper dumping position.

15 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

20 Referring to the drawings:

Figure 1 is a side elevational view of a loading device constructed in accordance with the invention.

Figure 2 is a longitudinal sectional view 30 through the movable chute forming a part of the invention.

Figure 3 is a plan view thereof.

Figure 4 is a plan view of the movable chute and scoop positioned therein.

35 Figure 5 is a longitudinal sectional view through the loading device.

Referring to the drawings in detail, the device includes a truck indicated generally by the reference character 5 which forms 40 the support for the loader.

The reference character 6 indicates the base of the loader which is mounted on the truck, and secured thereto by means of the bolt 7 that permits the base 6 to be adjusted in a horizontal plane with respect 45 to the truck.

Secured to the base 6 and arranged adjacent to the corners thereof are the supporting posts 8 and 9 respectively, the supporting posts 9 being of lengths to extend 50 above the endless conveyor, as clearly shown

by Figure 5 of the drawings, where they are connected by means of the shaft 10 on which the drum 11 is mounted.

One end of the drum is supplied with a 55 clutch face 12 that is engaged by the clutch member 13 that is splined on the shaft 10, and operated by means of the arm 14, to the end that when the clutch member is moved into engagement with the clutch face 12, 60 the shaft may be rotated to wind the cable 15 thereon. An operating handle indicated at 16 is removably supported at one end of the shaft 10 and affords means for rotating the drum but it is to be understood that 65 a suitable belt pulley may be supplied in place of the handle in order that mechanical power may be used for operating the shaft 10.

Mounted between the supporting posts 8 and 9 is a chute 17 that includes side members 18 and a bottom member 19, over which bottom member the carriers 20 operate. The carriers 20 comprise transversely disposed bars that have their ends connected to the belts 21, which belts operate over the 75 pulleys 22 mounted on the shaft 23 that has its ends mounted in the bearing members 24. Movement is transmitted to the shaft 23 by means of the chain 25 that operates over the sprocket 26 carried at one end of 80 the shaft 23, the chain receiving its motion from the sprocket 27 and shaft 10 on which it is mounted.

Thus it will be seen that simultaneously with the movement of the shaft 10, the endless carrier operates to deliver material to the upper end of the chute 17. On the opposite end of the shaft 10 is a sprocket 28 that transmits movement to the shaft 29 over which the endless carrier moves by 90 means of the chain 30 operating over the sprockets 28 and 31, the latter sprocket being secured to the shaft 29.

Secured to the lower end of the chute 17 are upwardly extended irons 32 that have 95 openings for the reception of the shaft 33 secured at the forward end of the swinging chute 34, the arms 35 of the irons 32 being also formed with openings and acting as bearings for the shaft 29.

This movable chute 34 has its forward or discharge end arranged above the endless

carrier so that material carried upwardly over the movable chute may be deposited onto the endless carrier.

The reference character 36 indicates a 5 scoop which may be employed in connection with the loading device, and as shown by Figure 2 of the drawings, the forward end of the scoop 36 engages the stop 37 arranged at the upper end of the chute to the 10 end that as the cable 15 is wound on its drum, the scoop will be tilted causing it to dump its contents onto the endless conveyor.

Should it be desired to handle manure, straw or the like material with the device, 15 the scoop is replaced by a forked member indicated at 38, which forked member may be moved over the movable chute in the same manner as the scoop 36 moves to unload its contents.

20 The scoop and forked member each includes a pivoted bail 39 and a sectional arm 40, the sections of the arm 40 being hingedly connected at 42, the hinged connection between the sections being adapted to be broken by a pull exerted on the flexible member 43, to the end that the bail 39 will be held in a predetermined condition until it is desired to dump the scoop or forked member connected therewith.

30 Openings 44 are formed in the bottom of the movable chute 34 through which openings prongs 45 extend so that the upper ends of the prongs 45 lie above the bottom of the chute 34 to engage material carried 35 over the chute, by the forked member 38.

A coiled spring indicated at 46 has connection with the lower ends 47 of the prongs in such a way that the prongs will be normally held to their active positions, but when 40 it is desired to use the scoop 36, the spring 46 may be moved to a position as shown by Figure 2 of the drawings, whereupon the prongs are held in their inactive positions and out of the path of travel of the scoop.

45 When the forked member is used, the prongs are moved to their active positions as shown by Figure 5 of the drawings, with the result that when the material carried by the forked member moves over the 50 prongs, and the forked member is returned to its loading position, the material moved over the movable chute is held against rearward movement by the prongs, to the end that when the forked member is again moved forwardly with a load of material, the succeeding load engages the load which has been previously deposited in front of the prongs, forcing the material over the forward end of the movable chute where the 55 same drops onto the endless conveyor and is carried to the upper or discharge end thereof.

In order that material will not move laterally from the movable chute at a point 60 where the material discharges onto the end-

less conveyor, guard plates 48 are provided, which guard plates are secured to the sides of the chute 17 as shown by Figure 1.

A chain indicated at 49 is secured to the movable chute 34 and may be passed over 70 the upper portion thereof and hooked at the opposite side of the movable chute, to the end that the hook 50 carried at one end of the cable 15 may be positioned over the chain 49 and the pivoted chute elevated to a position to permit the device to be moved from place to place.

75 In the use of the device, the supporting truck may be moved under the machine to a position as shown by Figure 3 of the drawings, whereupon the upper end of the chute 17 may be held in a position over a wagon or other suitable receiving vehicle, to the end that material may be readily and easily conveyed to the upper end of the chute 17 and deposited or loaded as before described.

80 In view of the foregoing detail description, it is thought that a further detail description as to the operation of the device is 85 unnecessary.

90 I claim:

1. A loading device including a truck, a base pivotally mounted on the truck, an inclined chute supported by the base, a chute pivotally connected with the first mentioned chute, a forked member movable over the last mentioned chute, means extending within the last mentioned chute and lying in the path of travel of the forked member for holding material moved over the last mentioned chute by the forked member, and means for moving the forked member over the chute.

95 2. A loading device including a truck, a base pivotally supported on the truck, a 105 chute supported by the base, an endless conveyor operating over the chute, a chute pivotally connected with the first mentioned chute, pivoted prongs extending through the last mentioned chute, resilient means for normally holding the prongs in their active 110 positions, a forked member adapted to move over the last mentioned chute and deliver material to the prongs, and means for moving the forked member over the last mentioned chute.

115 3. A loading device including a truck, a base pivotally mounted on the truck, a chute supported above the base, an endless conveyor operating over the chute, a chute pivotally supported adjacent to one end of the first mentioned chute, a forked member adapted to move through the latter chute, means extending into the last mentioned chute and lying in the path of travel of the forked member to receive material from the forked member, and means for operating the 120 endless conveyor and forked member.

125 4. A loading device including a truck, a chute supported above the truck, an endless 130

conveyor forming a part of the chute, a chute mounted adjacent to one end of the first mentioned chute, a carrier adapted to operate through the last mentioned chute, a bail forming a part of the carrier, a sectional arm connected with the carrier and bail, the sections of the arm being pivotally con-

nected, said arm adapted to normally hold the bail against movement, and said bail adapted to move upwardly when the arm is 10 broken.

In testimony that I claim the foregoing as my own, I have hereto affixed my signature.

DANIEL BRIGGLE.
